CLAIM

We claim the ornamental design for a bracelet, as shown and described.

DESCRIPTION

FIG. 1 is a perspective view of a bracelet showing my new design;

FIG. 2 is a left side elevation view of the bracelet in FIG. 1, the right, front, and rear side elevation views being a mirror image thereof;

FIG. 3 is a top plan view of the bracelet in FIG. 1, the bottom plan view being a mirror image thereof;

FIG. 4 is an exploded perspective view of the bracelet in FIG. 1;

FIG. 5 is a perspective view of the bracelet in FIG. 1, shown without the two removable jewelry strands and the removable hair band for clarity of illustration;

FIG. 6 is a left side elevation view of the bracelet in FIG. 5, the right, front, and rear sides being mirror images thereof; and,

FIG. 7 is a top plan view of the bracelet in FIG. 5, the bottom plan view being a mirror image thereof.

1 Claim, 5 Drawing Sheets
